UNITED STATES PATENT OFFICE.

JOHN J. KEENAN, OF NEW YORK, N. Y., ASSIGNOR TO MARGARET A. KEENAN, OF NEW YORK, N. Y.

APPARATUS FOR STOPPING VEHICLES.

1,203,006.

Specification of Letters Patent. Patented Oct. 31, 1916.

Application filed February 24, 1914. Serial No. 820,645.

To all whom it may concern:

Be it known that I, JOHN J. KEENAN, a citizen of the United States, and a resident of New York, county and State of New York, have invented a certain new and useful Improvement in Apparatus for Stopping Vehicles, of which the following is a full, clear, and exact specification.

This invention relates to a class of devices adapted to be used on public highways.

My invention has for its object primarily to provide an apparatus designed to be employed for stopping automobiles or like vehicles especially when the vehicle continues to travel after an accident has occurred, or when the vehicle is traveling faster than a given speed, and wherein are provided a series of posts, or guard members which are normally disposed in a trough arranged across a highway, and these guard members are pivotally connected to a common bar adapted to be movably adjusted for serving as means whereby the guard members may be simultaneously swung to extend vertically in spaced relation above the surface of the highway in emergency, or the guard members may be lowered to the same plane with the surface of the highway when the apparatus is not in use.

With these and other objects in view, the invention will be hereinafter more particularly described with reference to the accompanying drawings which form a part of this specification, and will then be pointed out in the claims at the end of the description.

In the drawings, Figure 1 is a fragmentary plan view of a number of highways showing the manner of employing in conjunction therewith my improved apparatus for stopping vehicles. Fig. 2 is an enlarged perspective view showing the apparatus when adjusted for stopping a vehicle. Fig. 3 is an enlarged fragmentary view of the apparatus, part of which is shown in section and part in detail. Fig. 4 is an enlarged perspective view of one of the guard members of the apparatus, and Fig. 5 is a view taken on the line V—V of Fig. 3, part of which is broken away.

The apparatus for stopping vehicles has two spaced supporting plates 10 and 11, one of which is disposed against each of the side walls of a trough, as 12, provided across a highway, as 13, and my apparatus is of a form whereby a number may be employed at

suitable parts of a single highway, as shown in Fig. 1, and two of the apparatus adapted to be simultaneously operated from a single station 14 may be arranged for use at intersecting highways, as shown in Fig. 2. The supporting plates 10 and 11 are alike in form, and these plates have their upper edges formed so that corresponding parts thereof are disposed on similar inclines, as at 15. The junctures of these inclines thereby provide depending shoulders 16 which serve as stops, and transversely through each of the shoulders is an opening.

In each pair of the openings of the supporting plates 10 and 11 is held a transverse rod 18, and on each of these rods is pivotally held a post, or guard member 19 made preferably of heavy metal so as to be adapted to withstand the weight of vehicles when traveling thereover. The posts 19 are similarly formed, and each post is substantially L-shaped to provide two angularly disposed arms 20 and 21. The arms 20 of the posts are approximately the same lengths as the inclined parts 15 of the edges of the supporting plates 10 and 11, and extending from the underside of the arm 20 of each post may be two flanges 22 and 23 each having its free edge tapered to conform with the pitch of the inclined parts of the supporting plates so that when the posts 19 are swung downwardly in the trough of the highway the top surface of the plates will be on the same plane with the surface of the highway for vehicles to pass thereover. The free end portion of the arm 21 of each of the posts 19 is enlarged, at 24, to provide a weight which is considerably heavier than the arm 20 of the post, and these weights serve to normally swing the posts in directions downwardly in the trough of the highway so that the post may be readily lowered therein. All of the weights 24 of the posts are pivoted, at 25, to a common bar 26 adapted to be movably adjusted for serving as means whereby the posts or guard members may be simultaneously swung to extend vertically in spaced relation above the surface of the highway in emergency, or the posts may be lowered in the trough when the apparatus is not in use.

For the purpose of moving the bar 26 to operate the posts, or guard members 19, I provide a form of mechanism, as 27. The mechanism 27 has a rod 28 having one of

its ends pivotally held to the pin 25 to which the opposed end of the bar 26 is pivoted, and the opposite end of said rod is pivoted to a crank 29. The crank 29 is held upon one end of a stud 30 journaled in a bracket 31, and on the other end of the stud is a bevel gear 32 which is in mesh with a bevel gear 33 held upon a vertically disposed shaft 34. The shaft 34 is 10 journaled in bearings provided in the station 14 which consists of a hollow base 36 and a hollow post 37 extending thereabove. The station of each apparatus is positioned alongside of the highway in a manner 15 whereby the hollow base thereof communicates with the trough of the highway. In order to permit the mechanism to be readily operated, the vertical shaft 34 is of a length to extend some distance upwardly in the 20 hollow post 37 of the station, and on the upper end of this shaft is a lever 38 which is movably disposed through a transverse slot 39 provided in the hollow post. By throwing the lever in one direction in the 25 slot 39 the shaft 34 will be revolved for rotating the bevel gears 33 and 32 which in turn will impart rotation to the crank 29. The rod 28 will thereby be directed for adjustably moving the bar 26 to swing the posts, or 30 guard members 19 so that the arms 20 thereof will be disposed at spaced intervals above the surface of the highway to prevent a vehicle from passing, or by throwing the lever in an opposite direction in the slot 39 35 the mechanism 27 will be reversely operated whereby the posts 19 will be lowered to their normal positions in the trough of the highway. The weights 24 of the arms 21 of the posts obviously serve to enable the 40 mechanism to be easily swung on their pivots, and these weights also tend to force the arms 21 of the posts in contact with the stops 16 of the supporting plates 10 and 11 to limit the downward movement of the 45 arms 20 when the posts are lowered so that the arms 20 are level with the highway.

When two of the apparatus are employed at the intersection of two highways, as shown in Figs. 1 and 2, and to permit both 50 apparatus to be operated in unison from a single station, in the hollow base 36 may be provided a second crank 40, Figs. 3 and 5, and this crank is held upon one end of a stud 41 journaled in a bracket 42. On the 55 other end of the stud 41 is a bevel gear 43 in mesh with the bevel gear 33 of the vertical shaft 34, and to this crank is pivoted one end of a rod 44 having its other end pivoted to the common bar 26 of the posts, 60 or guard member of the second apparatus. In this manner when the mechanism 27 is operated, as above described, the rotation of the shaft 34 and the bevel gear 33 will be imparted to the bevel gear 43 and to the 65 crank 40 for moving the rod 44. Both ap-

paratus will thereby be operated in unison for stopping vehicles when traveling from lateral directions toward one point.

In the foregoing description, I have embodied the preferred form of my invention, but I do not wish to be understood as limiting myself thereto, as I am aware that modifications may be made therein without departing from the principle or sacrificing any of the advantages of this invention; therefore I reserve to myself the right to make such changes as fairly fall within the scope of the appended claims.

Having thus described my invention, I claim as new and desire to secure by Letters Patent:

1. In an apparatus for stopping vehicles, the combination with a trough arranged across a highway, of a plurality of plates adapted to entirely cover said trough and lie flush with the surface of the highway, said plates being provided with an extension integral therewith and arranged at an angle thereto, together with means attached to said extensions for raising said plates to vertical position over said highway to form an obstruction therein.

2. In an apparatus for stopping vehicles, the combination with a trough arranged across a highway, of a plurality of plates adapted to entirely cover said trough and lie flush with the surface of the highway, said plates being provided with an extension integral therewith and arranged at an angle thereto and being pivoted to said trough, together with means connected to said extensions for swinging said plates into vertical position over said highway to form an obstruction therein.

3. In an apparatus for stopping vehicles, the combination with a trough arranged across a highway, of a plurality of plates arranged end to end, and adapted to entirely cover said trough and lie flush with the surface of the highway, extensions integral with said plates and arranged at an angle thereto, a bar pivotally connected to said extensions, and means attached to said bar for swinging the same endwise and thereby moving said plates into vertical position over said highway.

4. In an apparatus for stopping vehicles, the combination with a plurality of plates arranged end to end across a highway, of a housing for said plates sunk into said highway, said plates being hingedly connected to said housing and being adapted to lie flush with said highway when in horizontal position, weighted extensions connected to said plates at their hinged point, and mechanism connected to all of said extensions whereby said plates may be raised to vertical position over said highway, substantially as described.

5. In an apparatus for stopping vehicles,

the combination with a trough arranged across a highway, of a plurality of L-shaped posts hingedly supported within said trough, said posts having one arm formed in the shape of a plate and adapted to lie flush with the surface of the highway when in horizontal position, the other arm of said post being weighted and lying below the surface of the highway, together with means connected to said weighted arms for moving

same endwise and thereby raising said first mentioned arms to vertical position over said highway.

This specification signed and witnessed this twenty-first day of February, A. D. 15
1914.

JOHN J. KEENAN.
